UNITED STATES PATENT OFFICE

159,447

PLATE OR SIMILAR ARTICLE

George Rudd, Bedford, Ohio

Application November 14, 1949, Serial No. 6,023

Term of patent 14 years

(Cl. D44—15)

To all whom it may concern:

Be it known that I, George Rudd, a citizen of the United States of America, residing in Bedford, county of Cuyahoga, and State of Ohio, have invented a new, original, and ornamental Design for a Plate or Similar Article, of which the following is a specification, reference being had to the accompanying drawing, forming part thereof, wherein the figure is a plan view of a plate or similar article, showing my new design.

The dominant feature of my design resides in the ornamentation around the periphery of the plate as shown.

I claim:

The ornamental design for a plate or similar article, substantially as shown and described.

GEORGE RUDD.
